GUARD RAIL CLAMP

Filed Jan. 27, 1944

The present invention relates to the construction of railroads, and more particularly to the means for holding a guard rail in position adjacent to a traffic rail. It is an object of the invention to provide a clamp for holding a guard rail in position which is adjustably held in parallel relationship with the traffic rail in such manner that no intendedly permanent parts, such as spikes, are required to be removed to effect adjustment or replacement. Another object is to provide a clamp which is adapted to yield to oscillative movements of the clamp proper as caused by the contractive and expansive movements of the traffic rail; means for maintaining at minimum cost and labor, predetermined spacing between the traffic rail and attendant guard rail to compensate for flange wear and likelihood of damage to the points of the switch frog on the opposite side of the track, and, as a means providing at once, a rerailing frog, a protection against dragging brake rods and rigging, a guard against damage to crossing vehicle tires and for the general improvement in appearance, the invention affords inclined housings embracing all projecting elements of the assembly.

Other objects of the invention reside in providing a guard rail clamp whose adjustability results in avoiding the necessity of replacing the guard rail with a new one when worn and further, by virtue of its peculiar construction, the invention enables the guard rail to be installed on curves in the traffic rails without requiring that the guard rail be correspondingly bent. Moreover, all adjustments minute or otherwise, may be efficiently and quickly made by a single workman without dislocating the guard rail.

With the foregoing objects as paramount, the invention has further reference to certain features of accomplishment which will become apparent as the description proceeds, taken in connection with the accompanying drawing wherein:

Figure 1 is a plan view of a section of traffic rail with the guard rail attached by means of the present invention.

Figure 2 is a view in transverse section, taken on line 2-2 on Figure 1.

Figure 3 is a longitudinal sectional view, taken on line 3-3 on Figure 1.

Figure 4 is a perspective view with a portion of the traffic rail broken away.

Figure 5 is a detail view of one of the turn-out filler blocks, and

Figure 6 is a fragmentary perspective view of the traffic and guard rails, showing appurtenances including rerailment frogs, equipment guards and housings.

Continuing with a more detailed description of the drawing, reference is primarily made to Fig.

ure 1 wherein numeral 10 denotes a length of traffic rail to which is attached the guard rail 11. The invention includes the elements shown by which the guard rail 11 is adjustably held in parallel relationship with the traffic rail 10 in such manner that no intendedly permanent parts, such as spikes, are required to be removed to effect adjustment or replacement. These elements consist primarily of a curved, C-shaped yoke 12 whose body lies beneath and spans the rails 10 and 11 and whose inwardly turned ends confront the outer flange faces of these rails. One end of the yoke 12 is obliquely cut at a (Figure 1) and bears against a correspondingly inclined surface of a wedge key 13, interposed between the end a of the yoke and the flange of the guard rail 11.

The opposite end of the yoke 12 is curved at b in a plane at right angles to the longitudinal axis of the yoke body and lies in a correspondingly curved socket or recess formed in the face of a take-up block 14, interposed between this end of the yoke 12 and the outer face of the flange of the traffic rail 10. It is apparent from the foregoing that creeping of the traffic rail as a result of expansion and contraction in hot and cold weather or by vibration will be compensated for, in view of the provision for limited oscillation at the point b, which is, in effect, a pivotal point, allowing the end of the yoke adjacent the traffic rail to move with the rail while the opposite end remains stationary, with the result that the guard rail 11 will be held against movement.

Lying between the traffic rail and guard rail is a pair of complementary spacing blocks 15 whose confronting sides are not only tapered at c but are interlocking by virtue of the tongue and groove d (Figures 2 and 3). Obviously, the taper or wedge effect will increase or decrease the width of the space between the rails upon movement in counter directions of the blocks 15, while the tongue and groove will preclude any possibility of relative vertical displacement of the blocks.

Each of the blocks 15 has a shank in the form of a continuous rod 16, the rods extending in parallel relationship with the traffic rail 10 in opposite directions and are threaded at their ends. The ends of the rods 16 extend through suitable apertures in turn-out filler blocks 17, interposed between the traffic rail 10 and the turned out ends of the guard rail, as shown.

The turn-out filler blocks 17, one of which is shown in detail in Figure 5, each consist of a body shaped to conform to the space between the rails at the turn-out and having a transverse flange 18

beneath the outer or wide end, apertured at 19 (Figure 5) to receive the threaded end of a rod 16. The opposite or narrow ends of the blocks 17 are transversely slotted at 20 to accommodate bolts 21, which extend from one to the other of the rails, holding the turn-out ends of the guard rail in strict parallelism with the traffic rail.

Returning to the guard rail clamp proper, it will be observed, especially in Figure 1 that the wedge block 13 against which the oblique end *a* of the yoke 12 bears, is provided with an ear 22 adjacent the larger end thereof. This ear is apertured to correspond with an opening in the bend of the yoke and a bolt 23 is passed through the aperture and opening. A spring washer or compression spring 24 (Figure 1) is placed over the end of the bolt and a nut 25 bears on the spring thereby holding the yoke and block 13 in secure relationship, yet allowing for a limited degree of movement under tension. A lock washer 26 is also disposed on the end of each of the shanks or rods 16 of the spacer blocks 15 in advance of the nuts 27 thereon.

One of the spacer blocks 15, as apparent in Figures 2 and 3, is provided with downwardly depending lugs 28 which straddle the yoke 12 intermediate its ends. These lugs maintain assembled relationship of the blocks and yoke, preventing dislocation of the latter yet allowing for relative sliding movement of one of the wedge blocks 15, for the purpose to be made manifest in the description of operation to follow presently.

In operation, the guard rail 11 is arranged in parallel relationship with the traffic rail 10 and the yoke 12 is passed transversely under the rails with its ends in confronting relation to the outer faces of the rail flanges. The pivot block 14 is set in position with the arcuate end of the yoke resting in the conformably shaped recess therein. The wedge block 13 is thrust between the oblique end of the yoke and the flange of the guard rail and the bolt 23 is passed through the apertures of the ear 22 and yoke.

Before tightening the bolt 23 however, the spacer blocks 15 are positioned between the rails 10 and 11 in the manner shown with their shanks 16 extending towards the ends of the guard rail.

The turn-out blocks 17 are then placed between the turn-outs and the traffic rail so that the shanks 16 will pass through the apertures 19 in the blocks 17. When the turn-out blocks are so positioned as to properly space the rails, nuts 27 are set and the wedge block or key 13 is tightened by drawing up the bolt 23. Afterwards, the turn-out blocks are driven up tight and nuts 27 are firmly thrust down upon the lock washers. The wedging action of all of the parts, that is, the wedge key 13, spacer blocks 15 and turn-out blocks 17, positively secure the rails against accidental displacement, although it is apparent that longitudinal movement of the traffic rail is still permitted by virtue of the pivot block 14 without moving the guard rail 11.

Should it become necessary to move the guard rail 11 closer to the traffic rail 10 to compensate for wear on the ball of the guard rail, the bolt 23 of the wedge key 13 is loosened as well as the nuts 27 of the shanks 16. The turn-out blocks are moved outward and the spacer blocks 15 are adjusted by forcing the shanks 16 inwardly. When proper spacing of the rails is thus accomplished, the wedge key 13 is thrust further under the end of the yoke 12 to take up the slack, after which the nut 25 is tightened on bolt 23.

It is apparent from the foregoing that all ad-

justments and even the initial installation on guard rail replacements can be accomplished by a single trackman with a track wrench in but a short period of time. Moreover, a feature of importance lies in the fact that unlike conventional types of guard rail clamps, the present invention enables a guard rail to be placed on a curve in the traffic rail by virtue of the special shape of the turn-out blocks 17.

Also, minute spacing of the rails is possible by reason of the inclined conforming faces of the spacer blocks 15 and the positive means of securing thereof.

Shown in Figure 6 is a rerailing frog 29 one of which is disposed at each end of the guard rail 11. This frog consists of a body of a length equal to the width between the rails 10 and 11, one side of which is flush with the wide end of the turn-out blocks 17 and curves downwardly towards the opposite edge, thus presenting a surface upon which the flange of a derailed wheel may ride to resume its position on the ball of the traffic rail 10. It will be observed that the end of the body 29 next adjacent to the traffic rail is in no way secured to the rail, but is, in fact positioned so that the end of the guard rail will abut thereagainst. This arrangement provides for the usual expansive and contractive movements of the traffic rail but prevents movement of the guard rail. It will be observed that the outer end of the body 29 has a curved protuberance 30 rising into alignment with the turned-out end of the guard rail. This is not only a shield for the ends of the guard rail as an insurance against reversal of the trucks of a railway car, likely to result in serious wrecks but also prevents displacement of a derailed wheel, once it rides upon the frog. Also, the frog lends materially to the appearance of the installation in city street and has the added utilitarian feature of protecting vehicle tires from injury on the otherwise sharp ends of the guard rail.

In addition to the rerailing frog 29, the invention provides symmetrically shaped housings 31, one concealing the pivot end of the yoke 12 while the other, similarly shaped, covers the wedged end of the yoke. The curved or inclined exteriors of these housings improves the appearance of the installation as well as protecting the tires of vehicles passing thereover. They are so mounted as to be readily removed when adjustments in the spacing of the rails are needed and add little to the cost of the assembly.

Manifestly, the construction and process as shown and described is capable of some modification and such modification as may be construed to fall within the scope and meaning of the appended claims is also considered to be within the spirit and intent of the invention.

What is claimed is:

1. In combination with relatively parallel guard turnout and traffic rails, a guard rail clamp including a C-yoke transversely under-lying said rails, whose inwardly turned ends confront the outer web faces of said rails, one of said ends being inclined with respect to the adjacent rail web and the other end arcuated, a wedge cooperating with said inclined yoke end to effect end-wise displacement of said wedge, a pivot space block interposed between the arcuated end of said yoke and the adjacent rail web and having a recess correspondingly receiving said arcuated end for limited oscillation, cooperative expanding wedge blocks interposed between said rails intermediate the ends of said yoke having oppositely extending shanks, turn-out blocks on

each side of said wedge blocks having wedging engagement between confronting sides of said turnout and traffic rails and apertured to receive said shanks and means on the ends of said shanks for actuating said wedge blocks.

2. In combination with a traffic rail and a relatively parallel guard rail, a guard rail clamp comprising a yoke underlying said rails in transverse relationship and having inwardly turned ends, means interposed between one of said ends and an adjacent rail web for changing the relative spacing of said rails, means between the opposite end of said yoke and the opposite rail web for retaining said yoke for limited oscillating movement, cooperating means intermediate said rails adjacent said yoke for imposing a wedging action on said rails, integral shanks carried by said cooperating means and spacing means on each side of said cooperating means having wedging engagement with confronting sides of said traffic and guard rails and adapted to receive said shanks and through which relative spacing of said rails is effected and maintained.

3. A guard rail clamp including a C-shaped yoke, one end of which confronts the outer web face of said guard rail, the other end confronting the outer web face of a relatively parallel traffic rail, means for imposing a wedging action between one end of said yoke and an adjacent rail, means oscillatably retaining the opposite end of said yoke against the companion rail, correspondingly inclined wedge blocks interposed between said rails having oppositely extending shanks, turn-out blocks wedgingly held between confronting sides of said rails at the ends of said guard rail and receiving said shanks and means for effecting longitudinal movement of said shanks to effect displacement of said turn-out blocks, wedge blocks and yoke to change the relative spacing of said rails.

4. In a guard rail clamp, a C-shaped member adapted to underlie a guard rail and a relatively parallel traffic rail, means to exert a wedging action between one end of said yoke, and the outer face of an adjacent rail means holding one end of said yoke for limited oscillating movement to compensate for movement of said traffic rail, cooperating means intermediate said rails for imposing a wedging action thereon to compensate for variations in the relative spacing thereof, shanks carried by and extending in opposite

directions from said latter means, and means also held in wedging engagement with and intermediate said rails and spaced from said cooperating means and adapted to receive said shanks to effect actuation of said cooperating means preparatory to changing the relative spacing of said rails.

5. A guard rail clamp including in combination with a guard rail and traffic rail, means adjustably holding said rails in spaced relationship for limited longitudinal displacement, wedge blocks intermediate said rails having cooperatively inclined confronting faces and provided with oppositely extending shanks, space blocks in wedging engagement between said rails at each end of said guard rail and apertured to receive said shanks and means carried by the ends of the latter for changing the relative positions of said wedge blocks preparatory to adjusting the relative spacing of said rails.

6. A guard rail clamp including in combination with a guard rail and a traffic rail, means adjustably holding said rails in spaced relationship, complementary wedge members interposed between said rails and having oppositely extending shanks, space blocks wedged between said guard and traffic rails and disposed on each side of said wedge members and through which said shanks movably extend and means adjustably carried by the end of said shanks for changing the positions of said wedge members in corresponding relation to changes effected in the relative positions of said yoke and space blocks preparatory to adjusting the relative spacing of said rails.

7. A guard rail clamp including in combination with a guard rail and the traffic rail to which it is attached, a C-yoke underlying said rails a wedge interposed between one end of said yoke and an adjacent rail, the other end of said yoke being in oscillatable engagement with the companion rail, cooperating wedge means intermediate said rails having threaded shanks, space blocks wedged between said guard and traffic rails in opposing relationship with said wedge means and receiving said shanks and means carried by said shanks for displacing said wedge means in corresponding relation to changes made in the positions of said yoke and space blocks preparatory to varying the relative spacing of said rails.
